UNITED STATES PATENT OFFICE.

WILLIAM BOEKEL, OF PHILADELPHIA, PENNSYLVANIA.

GAS-BURNER.

SPECIFICATION forming part of Letters Patent No. 358,332, dated February 22, 1887.

Application filed June 13, 1885. Serial No. 168,578. (No model.)

To all whom it may concern:

Be it known that I, WILLIAM BOEKEL, a citizen of the United States, residing in the city and county of Philadelphia, State of Pennsylvania, have invented a new and useful Improvement in Gas-Burners, which improvement is fully set forth in the following specification and accompanying drawings, in which--

10 Figure 1 represents a vertical section of a gas-burner embodying my invention. Fig. 2 represents a horizontal section in line *xx*, Fig. 1. Fig. 3 represents a horizontal section in line *yy*, Fig. 1.

15 Similar letters of reference indicate corresponding parts in the several figures.

My invention relates to improvements in gas-burners; and it consists in the various details in construction and arrangement of parts, 20 as hereinafter set forth.

Referring to the drawings, A represents a gas-pipe which is connected with a supply-service pipe in any suitable manner. To the bottom of said pipe is secured a chamber, B, 25 from which rises a circular row of burners, C, said chamber being also sustained by a rod or pipe, C', which is connected with the chamber, passes through the pipe A, and is attached at top to a plug or coupling, D.

30 Surrounding the burners C is a chimney, E, and above the same is a flue, F, for the escape of the products of combustion. Surrounding the flue F is a flue, G, for the admission of air to the burners, it being noticed that the flue 35 F is suitably secured to the top cap, H, and the flue G to a chamber, J, below said cap. Attached to said chamber J, and in communication therewith, are tubes K, which reach to a chamber, L, the latter surrounding the burn- 40 ers C and sustaining the chimney E, and adapted to convey air to said burners.

Within the space between the burners C and

chambers J is a deflector, M, which is an annulus of V shape in cross-section, adapted to direct air between the burners and within the 45 same and also outside thereof, whereby the flame is supplied with air both on its interior and exterior.

It will be seen that when the burner is lighted the products of combustion escape 50 through the flue F. This also heats the pipe A, so that the gas is conveyed to the burners in a warm or heated condition. Again, the air ascending, the flue G is heated by the hot flue F, and so directed, by means of the pipes 55 K and chamber L, to the burner in a warm or heated condition, so that a brilliant light is produced.

A portion of the pipe A just above the burners is widened, as at A', and formed of 60 material that may become incandescent and act as a reflector, and likewise produce an enlarged chamber for heating the gas as it descends in its passage to the burners.

Having thus described my invention, what I 65 claim as new, and desire to secure by Letters Patent, is--

1. The gas-pipe A, with burners C, in combination with air-chamber L, surrounding said burners and having deflectors M, chimney E, supported by said chamber L and having flue F, flue G, surrounding said flue F and open at bottom and leading into the air-chamber J, and tubes K, connecting air-chambers J and L, substantially as and for the 75 purpose set forth.

2. A circular row of burners and a surrounding air-chamber, in combination with a double-acting deflector, substantially as described.

WM. BOEKEL.
